UNITED STATES PATENT OFFICE.

THOMAS BURKE FOGARTY, OF NEW YORK, N. Y.

IMPROVEMENT IN GAS-BURNERS.

Specification forming part of Letters Patent No. 135,979, dated February 18, 1873.

To all whom it may concern:

Be it known that I, THOMAS BURKE FOGARTY, of New York, in the county and State of New York, have invented a certain new and useful Improvement in Gas-Burners, of which the following is a specification:

Nature and Object of the Invention.

The said invention relates to gas-burners in which it is desirable to supply the central jet with an external supply of gas; and it consists in extending the body of the burner or tube that screws on the gas-pipe upward around the tip or nib, with a concentric space between them, the tip being movable and formed with a flange that opens and closes internal passages that regulate the flow of gas external to the central flame.

Description of the Drawing.

To enable others skilled in the arts to which it appertains to make and use my invention, I will proceed to describe its construction and operation with reference to the drawing.

Figures 1 and 2 are longitudinal sections of a gas-burner made according to my invention, and the smaller figures are transverse sections made, respectively, on the dotted lines through their centers.

The burner tube or barrel *a*, which screws upon the gas-pipe, is made with an internal flange, *b*, through which is drilled a series

of holes that correspond in position with a similar series of holes in the flange *c* of the nib *d*. The tip or nib has a spur, *e*, that projects through a slot in the barrel of the burner, by which it may be moved radially to afford a free passage for the gas through the holes; or it may be moved to close the holes entirely, or regulated at any intermediate point to adjust the flow of gas through them, as may be required to feed the flame after being diffused through the annular opening that surrounds the flame.

The tip may be of lava, cement, or any other material that admits of its being moved slightly to adjust a series of openings at its base. The flange on the tip must close the slot in which the spur works to prevent the admission of air. By this arrangement the supplementary supply of gas may be adjusted without appreciably affecting the position of the flame.

Claim.

I claim as my invention—

The interior movable tip *d* with perforated collar *c* resting upon the perforated ledge of the casing, when the parts are combined to operate in the manner set forth.

THOS. B. FOGARTY.
